FIRE LIGHTER

Serafin Santeago Fernandez, Las Vegas, Nev.

Application November 14, 1935, Serial No. 49,812

3 Claims. (Cl. 44—36)

The present invention relates to new and useful improvements in fire lighters and has for its primary object to provide, in a manner as hereinafter set forth, a device of this character embodying a novel construction, combination and arrangement of parts through the medium of which a fire in a furnace, stove or the like may be automatically lighted at a predetermined time.

Another very important object of the invention is to provide means for lighting a fire at a predetermined time through the medium of chemicals.

Other objects of the invention are to provide a fire lighter which will be comparatively simple in construction, strong, durable, highly efficient and reliable in use, compact and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:—

Figure 1 is a view principally in side elevation of a fire lighter constructed in accordance with the present invention, portions being shown in section.

Figure 2 is a view in vertical section through the device.

Figure 3 is a detail view in perspective of the vertically movable cone.

Figure 4 is a detail view in perspective of the cone cover.

Referring now to the drawings in detail, it will be seen that the embodiment of the invention which has been illustrated comprises a cylinder 1 of any suitable material, preferably metal, having mounted on its lower end portion apertured ears 2 for the passage of securing elements 3 for anchoring the device to a suitable base or support. Rising from the upper end of the cylinder 1 are ears 5 which are apertured to receive the threaded ends of a handle 6, said handle being secured in position by nuts 7. Fixed at an intermediate point on the handle 6 is a bail 8 having journaled thereon a roller 9.

Fixed in the cylinder 1 is an elevated bottom 10 having mounted thereon a funnel 11. Connected to the lower end of the funnel 11, as at 12, is an elbow or the like 13 which extends through an opening 14 provided therefor in the lower portion of the cylinder 1 and which has connected thereto an inclined pipe 15. Mounted on the lower end of the pipe 15 is a substantially spoon-

shaped pan 16 which, as illustrated to advantage in Figure 1 of the drawings, communicates with said pipe 15.

Mounted for vertical movement in the funnel 11 is a cone 17 having vertical chambers 18 and 19 extending therethrough. The chamber 18 is for the reception of a charge of peroxide of sodium, as at 20, and the vertical chamber 19 is for the reception of tannic acid, as at 21. When the cone 17 is resting in the funnel 11 said funnel 10 closes the vertical chambers 18 and 19 at their lower ends.

The cone 17 is also provided with a centrally located well 22 from which a reduced passage 23 extends to the lower end of said cone. Mounted 15 in the well 22 is a substantially cup-shaped container 24 for the reception of water, as at 25. The bottom of the container 24 is provided with an opening 26 which is tapered to form a seat for a valve 27, said valve being seated by a spring 28. 20

Mounted on the cone 17 is a removable cover 29 for the chambers 18 and 19 and the container 24. Threaded shanks 30 rise from the top of the cone 17 and extend through the cover 29 and mounted on said shanks are wing nuts 31 which 25 secure said cover 29 in position. Depending from the handle 6 is a stem 32 which extends slidably through the cover 29 into the container 24 and which is engageable with the valve 27 for unseating said valve.

Eyes 33 are mounted on the cover 29 and secured therein is a flexible cord or the like 34 which is windable on the alarm winding stem 35 of a conventional time clock 36 for elevating the cone 17 at a predetermined time. As best seen in 35 Figure 1 of the drawings, the lower portion of the string 34 is looped, the loop passing through the eyes 33 and through openings 37 in the handle 6 and then passing over the roller 9.

Briefly, the operation of the device is as follows:—

When the alarm of the clock 36 is released, the string 34 is wound on the alarm stem 35 thereof for raising the cone 17 out of engagement with the funnel 11, thus permitting the chemicals in 45 the chambers 18 and 19 to drop into the elbow 13 and flow by gravity into the tray 16 through the pipe 15. As upward movement of the cone 17 continues the stem 32 engages and unseats the valve 27 against the tension of the coil spring 28 50 for releasing the water 25 in the container 24 and permitting said water to flow into the tray 16. Immediately upon contact of the water with the chemicals in the tray 16 ignition occurs for light- 55

ing the fuel in the furnace, stove or the like. It should perhaps be here stated that the tray 16 is located, for example, immediately beneath the grate of a furnace or stove on which fuel has 5 previously been placed.

It is believed that the many advantages of a fire lighter constructed in accordance with the present invention will be readily understood, and although a preferred embodiment of the device is 10 as illustrated and described, it is to be understood that changes in the details of construction and in the combination and arrangement of parts may be resorted to which will fall within the scope of the invention as claimed.

15 What is claimed is:—

1. A fire lighter comprising a supporting structure, a funnel mounted on said supporting structure, a tray communicating with said funnel, a vertically movable cone mounted in the funnel, 20 said cone having chambers therein, for the reception of chemicals ignitable upon being contacted by a liquid, closed by the funnel, a container, for the reception of water, mounted in the cone, said container having a discharge opening 25 therein, a spring actuated valve closing said opening, means for elevating the cone out of engagement with the funnel, and means mounted on the supporting structure engageable with the valve for unseating said valve when the cone is 30 elevated.

2. A fire lighter comprising a supporting structure, a funnel mounted on said supporting structure, a tray communicating with said funnel, a vertically movable cone mounted in the funnel, 35 said cone having vertical chambers therein for the reception of chemicals ignitable upon being contacted by a liquid, the funnel closing said vertical chambers at their lower ends when the cone

is engaged with said funnel, means for elevating the cone for discharging the chemicals into the tray, a container, for the reception of water, mounted in the cone and having a discharge opening communicating with the tray, a spring 5 actuated valve closing the discharge opening, and a stem mounted on the supporting structure and extending into the container for engaging and unseating the valve for causing the water to flow into the tray. 10

3. A fire lighter of the class described comprising a cylinder, an elevated bottom mounted in said cylinder, a funnel mounted on said bottom, a conduit connected to the bottom of the funnel, a tray connected to the conduit and communicating therethrough with the funnel, a cone mounted for vertical movement in the funnel, said cone having vertical chambers extending therethrough for the reception of chemicals ignitable upon being contacted by a liquid, the funnel closing said 20 chambers at the lower ends thereof when the cone is engaged with said funnel, said cone further having a centrally located well therein, a container, for the reception of water, mounted in said well, said container having a discharge opening in its bottom for communication with the tray, a spring actuated valve mounted in the well and engageable in the opening for closing the same, a cover for the chambers and the container 25 removably mounted on the cone, means connected to the cover for elevating the cone for releasing the chemicals into the tray, a handle mounted on the cylinder, and a stem depending from said handle and extending slidably through the cover into the container for engaging and unseating the valve for releasing the water into the tray. 30
